PHONOGRAPH SWITCH.

Theodore C. Riebe, Chicago, Ill., assignor to Automatic Electric Laboratories, Inc., Chicago, Ill., a corporation of Delaware

Application July 30, 1943, Serial No. 496,763

2 Claims. (Cl. 200—52)

This invention relates to switches, and more particularly to snap-action switches particularly designed for use with phonographs.

In phonographs of either the recording or reproducing types it is common to provide a sequence operation mechanism which is controlled in accordance with the position of the tone arm relative to a record on the turntable. In reproducing phonographs and in recording phonographs utilizing pregrooved records, it is particularly desirable to provide a switch to be actuated by the tone arm which will be snap-acting, positive and accurate in operation and which will require a minimum force applied by the movement of the tone arm.

In telephone conversation recording systems of the type installed at the subscriber's station, there is provided an arrangement utilizing two phonograph turntables and recording tone arms which are controlled by a sequence operation mechanism so that, if the conversation exceeds the capacity of a single record, the second turntable and record thereon will become operative to continue to record the conversation shortly prior to the end of the first record. In such arrangements it is desired to provide recording apparatus which is simple to operate, and hence pregrooved records are provided. In order that a clear record be obtained, it is necessary that the tone arm be required to do as little additional work as possible. Accordingly, the present invention is directed to an improved switch which is to be actuated by the tone arm, and which will fulfill the previously mentioned requirements.

It is an object of this invention to provide an improved switch for phonographs which is simple in construction and reliable in operation.

Other and further objects of this invention will become more readily apparent by reference to the following description taken in connection with the accompanying drawings, wherein—

Figure 1 is a side view of a phonograph turntable and tone arm provided with the switch comprising the present invention.

Fig. 2 is a top view of the apparatus of Fig. 1 showing the tone arm in its initial position; and

Figs. 3 and 4 are side and top views, respectively, which illustrate the switch mechanism when the tone arm is near the end of the record.

Referring more particularly to the drawings, there is shown a mounting panel 11 of a phonograph apparatus, above which is supported a turntable 12 and a tone arm 13 which, in telephone recording systems, comprises a record cutting arm. A phonograph switch 14 secured to

the mounting panel 11 is arranged to be actuated by a member 15 attached to the record cutting tone arm 13. The switch 14 comprises a base plate 16 secured to the mounting panel 11 by suitable fastening means, such as screws 17. The base plate 16 is provided with a stud 18 which supports a bell crank lever switch arm 19, which is biased in one direction by one leaf 21 of a switch assembly 22 supported from the base 16 by an upturned projection 23. The spring leaf 21 exerts pressure against an insulating spacer member 24 which engages the outer extremity of one arm of the bell crank switch lever 19. The other arm of the bell crank lever 19 is arranged to move within the limits of a guide structure 25 secured to the base 16. The outer extremity of this arm of the bell crank lever 19 is provided with a cam surface 26, the purpose of which will subsequently become apparent. At an intermediate point on this portion of the switch arm 19 adjacent the cam surface 26, there is provided an upturned member 27 which is arranged to cooperate with the outer extremity of a catch lever 28. The catch lever 28 is suitably supported from the base 16 by a stud 29, and the lever is spring-biased by a spring 31 attached to the lever 28 and connected to an upturned lug 32 formed on base member 16. The outer extremity of the catch arm 28, therefore, is biased in a direction toward the upturned lug portion 27 of the switch arm 19. Adjacent the outer extremity of the catch arm 28 there is provided a notch or step 33, the shoulder of which, in the position shown in Fig. 2, appears against an upturned lug 27 of the arm 19 to prevent that arm from being moved by the spring 21 to close the contacts 34 of the switch assembly 22. The switch 14 may be enclosed by a suitable cover 35 attached to the mounting panel 11 by suitably arranged mounting portions 36 which are held in position by a plurality of fastening means such as screws 37. The switch 14 is actuated by the member 15 attached to the tone arm 13, and this member is provided with a depending stud or roller 38 which is arranged to engage the cam surface 26 of the bell crank switch arm 19 and also an intermediate portion on the catch lever 28.

The operation of the switch will be understood more readily by referring more particularly to Figs. 3 and 4, which show the tone arm 13 in the position near the end of a phonograph record. From this it will be observed that the depending roller or stud 38 of the switch actuating member 15 is in engagement with an inter-

mediate portion of the catch lever 28, which has been moved so that the shoulder of the notch 33 is no longer in engagement with the upstanding lug 27 on the switch arm 19. The movement of the lever 28 is such that the lug 27 is disengaged from the shoulder of the notch 33, whereby the spring 24 will actuate the bell crank switch arm 19 and close the contacts 34 of the switch assembly 22 with a snap action. It may be assumed that the operation of the switch contacts 34 has brought about the deenergization of the turntable motor, which drives the turntable 12, so that there is no further movement of the record cutting arm 13. The attendant at the recording apparatus thereupon will restore the record cutting arm 13 to the side of the turntable 12 and replace the record on the turntable 12 with a new record. The movement of the arm 13 to the side of the turntable 12 moves the stud 38 through an arc, so that the cam surface 26 is engaged thereby so as to move the lever 19 back to a position shown in Fig. 2, whereupon the notch 33 in the catch lever 28 will again engage the upturned lug 27 of the switch arm 19, thereby resetting the switch 14 to its former condition. Even though the attendant may again move the arm 13 sufficiently so as to again engage the cam surface 26 of the arm 19 with the depending stud 38 of the actuating member 15, the switch 14 will be in proper operative condition when the attendant again places the arm 13 at the beginning of a new phonograph record.

It will readily be appreciated that when the depending roller 38 on the actuator 15 is moved by the tone arm 13 during the recording of a conversation into the vicinity of the cam surface 26 of the switch arm 19, there may be some movement of the lever 19, but this movement is rather small and the switch is not actuated because sufficient space is provided by the length of the notch 33 to permit this rather small movement. After the roller 38 has passed the highest point of the cam surface 26, no further effort is required on the part of the tone arm 13 until the catch lever 28 is engaged by the roller 38. Then, for a very short distance, effort is required of the tone arm 13 to permit the upturned lug 27 to escape, whereupon snap action of the switch occurs at a definite predetermined position of the record cutting arm 13.

While the above-described switch is particularly suited for use in telephone conversation recording systems or phonographs of the recording type using pregrooved records, it, of course,

will be appreciated that this switch is also suitable for use with other types of phonographs, including reproducing phonographs.

While this invention has been illustrated by a single preferred embodiment, it, of course, is to be understood that modifications may be made therein which are commensurate with the scope of the appended claims.

What I claim is:

1. The combination, in a phonograph, of a tone arm with a switch adapted to be actuated in response to certain movements of said tone arm, said switch comprising a switch arm having adjacent the free end thereof a reset cam surface and a catch member, a spring arranged to bias said switch arm toward a certain position, a pivotally mounted catch lever normally biased to engage said switch arm catch member to hold said switch arm in another position, and a switch actuating member carried by said tone arm and arranged when said tone arm is moved in one direction to disengage said catch lever from said catch member thereby to permit said switch arm to be moved to said certain position, and when said tone arm is moved in another direction to engage said switch arm cam surface thereby to move said switch arm catch member into a position to be re-engaged by said catch lever.

2. The combination, in a phonograph, of a tone arm and a snap action switch adapted to be actuated in response to certain movements of said tone arm, a switch actuating member mounted on said tone arm, said switch comprising a pivotally mounted switch arm having adjacent the free end thereof a reset cam surface and a catch member, a spring arranged to bias said switch arm toward a first position wherein said reset cam surface will be moved into the path of said switch arm actuating member, and a pivotally mounted spring-biased catch lever arranged to engage said switch arm catch member to hold said switch arm in a second position, said switch actuating member mounted on said tone arm being arranged to disengage said catch lever from said catch member so as to permit said biased switch arm to be moved to said first position when said tone arm is moved in one direction, and being arranged when said tone arm is subsequently moved in the opposite direction to engage said switch arm reset cam surface thereby to move said biased switch arm to said second position so as to permit said catch lever to re-engage said catch member.

THEODORE C. RIEBE.
